MILD DETERGENT COMPOSITIONS

Howard F. Drew, North College Hill, and Jack G. Voss, Wyoming, Ohio, assignors to The Procter & Gamble Company, Cincinnati, Ohio, a corporation of Ohio
No Drawing. Filed Apr. 20, 1959, Ser. No. 807,333
11 Claims. (Cl. 252—137)

This invention relates to combinations of synthetic detergents which have superior mildness characteristics. More particularly it relates to combinations of certain alkyl benzene sulfonates and tertiary amine oxides, which combinations are mild in their action toward the skin.

Alkyl benzene sulfonates having alkyl radicals ranging from about 9 to about 15 carbon atoms are widely used as household synthetic detergents. They are economical, and have good detergency, foaming, solubility, odor and color characteristics. However, in view of present day emphasis on mildness in detergent products and in view of published information (Schwartz, Perry and Berch, Surface Active Agents and Detergents, vol. II, page 377) that these synthetics are less mild than soap, it is desirable that these alkyl benzene sulfonates be rendered as mild as possible to the human skin.

Tertiary amine oxides, represented by the chemical formula

(the oxygen being attached to the nitrogen by a semi-polar bond), and conventionally indicated by the formula $R_1R_2R_3N \rightarrow O$, wherein R_1 is an alkyl radical containing about 10 to about 18 carbon atoms and R_2 and R_3 are each lower alkyl radicals, also are very efficient synthetic detergents with excellent detergency and foaming characteristics. However, like the above-mentioned alkyl benzene sulfonates, it is desirable that these amine oxides be rendered milder to the human skin.

The relative mildness to the human skin of the aforementioned alkyl benzene sulfonates and amine oxides can be determined by exaggerated exposures with test animals. In tests of extreme severity conducted on guinea pigs, for example, the alkyl benzene sulfonates and the amine oxides when used alone, cause a thickening of the skin of the test animal, usually accompanied by dryness and cracking of the skin.

It is an object of this invention to provide a composition containing a mixture of synthetic detergents which has excellent detergency characteristics and has a mildness to the skin markedly superior to the mildness of either of the component detergents alone.

It is another object of this invention to provide a cleansing composition containing a tertiary amine oxide and an alkyl benzene sulfonate, which are mildness additives for each other, and each of which is a highly efficient detergent and foaming agent.

It was found that certain mixtures of the amine oxides and alkyl benzene sulfonates described above exhibit superior and unexpected mildness characteristics. In certain ranges, and under comparable conditions of exposure, mixtures of these two detergents in solution are milder to the skin than either one alone. The aforementioned thickening, dryness and cracking of the skin of test animals under exaggerated exposures are markedly reduced and in some cases disappear. This mildness effect is very advantageous since combinations of the alkyl benzene sulfonates and amine oxides in the compositions of the present invention are very efficient, good foaming detergents. For example, if it is desired to make milder either the alkyl benzene sulfonate or the amine oxide, one of

2

the ingredients can be combined with the other as hereinafter described with no reduction in the desired detergency or sudsing on the basis of the total detergent present, since both ingredients are excellent in these properties.

The cleansing compositions of this invention having superior mildness characteristics comprise mixtures of alkyl benzene sulfonates having alkyl radicals ranging from about 9 to about 15 carbon atoms and tertiary amine oxides, having the formula $R_1R_2R_3N \rightarrow O$ wherein R_1 is an alkyl radical containing from about 10 to about 18 carbon atoms and R_2 and R_3 are each methyl, ethyl or propyl radicals, the ratio of the respective ingredients being in the range of about 20:1 to about 1:5, preferably about 10:1 to about 1:2.

The alkyl benzene sulfonates in the compositions of this invention are the water soluble salts, such as the alkali metal (e.g. sodium, potassium and lithium), ammonium and substituted ammonium (e.g. triethanolamine) salts, of sulfonated alkyl benzene in which the alkyl radicals range from about 9 to about 15 carbon atoms. Alkyl benzene sulfonates usually contain mixtures of alkyl radicals in this range. The preferred alkyl benzene sulfonate is one in which the alkyl radicals in the mixture average about 12 carbon atoms and are derived from a polypropylene which is predominantly tetrapropylene. This alkyl benzene sulfonate is hereinafter referred to as dodecyl benzene sulfonate and is most commonly used as a sodium salt.

Alkyl benzene sulfonates can be produced in a number of ways. The usual processes involve first the preparation of a satisfactory source for the alkyl component such as an olefin, e.g. polypropylene, or an alkyl halide, e.g. chlorinated kerosene. Alkyl benzene is formed by condensing the olefin or alkyl halide with benzene in a reaction of the Friedel-Crafts type using a catalyst such as $AlCl_3$ or HF. The alkyl benzene is then sulfonated, purified, converted to the desired salt and worked up to the desired form, e.g. powder, granule or paste. The manufacture of alkyl benzene sulfonates is described in the Journal of the American Oil Chemists' Society, 35, 520-24 and 528-31 (1958).

The tertiary amine oxides in the compositions of this invention have the formula $R_1R_2R_3N \rightarrow O$ wherein R_1 is an alkyl radical containing from about 10 to about 18 carbon atoms, and R_2 and R_3 are each methyl, ethyl or propyl radicals. If R_1 is shorter in chain length than about 10 carbon atoms, the solubility of the resulting amine oxide is reduced. If R_1 is longer in chain length than about 18 carbon atoms, the solubility of the resulting amine oxide is reduced to an undesirable point for detergency purposes. Amine oxides in which R_1 contains 12 to 16 carbon atoms have preferred solubility, foaming and detergency characteristics, particularly when R_1 is a straight, saturated chain. If R_2 and R_3 are longer in chain length than 3 carbon atoms, the resulting amine oxide is not sufficiently soluble to be desirable as a detergent. Those higher alkyl tertiary amine oxides in which R_2 and R_3 are methyl radicals also have preferred detergency, solubility and foaming characteristics for use in this invention. The lauryl dialkyl amine oxides and those tertiary amine oxides in which the R_1 alkyl radicals are predominantly the mixture of lauryl and myristyl radicals found in fractionated coconut oil fatty alcohol are particularly desirable compounds in the compositions of the present invention.

The higher alkyl tertiary amine oxides of this invention can be produced by oxidizing higher alkyl tertiary amines with an oxidizing agent such as hydrogen peroxide or Caro's reagent (ammonium or potassium persulfate dissolved in concentrated sulfuric acid). Higher alkyl tertiary amines can be produced by alkylating a secondary

amine; for example, lauryl dimethyl amine can be produced by reacting dimethyl amine with lauryl alcohol or a derivative thereof such as lauryl iodide. Examples of the higher alkyl groups in the tertiary amine oxides which can be used in the compositions of this invention include primary alkyl groups such as cetyl and oleyl groups which are derived from fats and oils or petroleum derived olefins, secondary alkyl groups such as an α -methyl pentadecyl group derived from an α -olefin, substituted alkyl groups such as a 2-hydroxylauryl group, and non-aromatic interrupted alkyl groups such as a carbamide substituted alkyl group. Methods for making amine oxides are described in British Patent No. 437,566.

Examples of amine oxides which can be used in preparing the compositions of the present invention are:

Lauryl dimethylamine oxide
 Myristyl dimethylamine oxide
 Cetyl dimethylamine oxide
 2-hydroxylauryl dimethylamine oxide
 α -Methylundecyl dimethylamine oxide
 Oleyl dimethylamine oxide
 Lauryl methyl ethyl amine oxide
 Lauryl diethylamine oxide
 2-diethyl amino ethyl lauramide oxide
 Myristyl diethylamine oxide
 Cetyl diethylamine oxide
 α -Methylpentadecyl diethylamine oxide
 Oleyl diethylamine oxide
 Myristyl ethyl propyl amine oxide
 Lauryl dipropylamine oxide
 Myristyl dipropylamine oxide
 Cetyl dipropylamine oxide
 Cetyl methyl propylamine oxide
 Coconut alkyl dimethylamine oxide wherein the higher alkyl radicals are predominantly the mixture of lauryl and myristyl radicals found in coconut oil fatty alcohol (such a mixture can be obtained by taking the "middle cut" of fractionated coconut oil fatty alcohol)

The unexpected mildness resulting from the combination of alkyl benzene sulfonates with amine oxides in accordance with the present invention appears to be specific only to the compounds designated. For example, when the aforementioned tertiary amine oxides were mixed with the salts of sulfated coconut oil fatty alcohols and tested for mildness, the mixtures were not significantly milder. Coconut oil alkyl sulfates, like alkyl benzene sulfonates, are widely used synthetic detergents which reportedly could be made milder.

In the testing of detergent compounds and compositions for mildness and for the unexpected mildness effect, skin is contacted by immersion or other means with a solution of the detergent under standardized conditions as more fully described below. A 1 to 10 scale is used to rate the effects of prolonged exposure on the skin. Grade 10 represents ideal or perfect skin (soft, smooth and flexible) and the effect of a theoretically perfectly mild detergent; grade 1 represents severely irritated skin. Other values represent gradations of severity between these extremes. Grade 1 in a guinea pig immersion test indicates severely thickened, dry, cracked and bleeding skin, i.e. extreme irritation. Grade 1 in exaggerated tests on human subjects indicates severe redness and dryness of the skin. Thus, the exaggerated exposure tests on animals are much more extreme than those conducted on human subjects.

It was found that there is a good correlation between the results of exaggerated exposure tests on animals and the results of normal use tests on humans, and that the former can be relied on to grade the relative mildness of detergents toward the human skin. This correlation was determined in the following manner. A series of standardized, graded guinea pig immersion tests were run on

each of thirteen detergent compositions and on the basis of these results the compositions were rated in order of mildness. All compositions were within the normal range of mildness exhibited by washing compositions in use for many years. The order of mildness on humans was determined by extensive tests. A panel of about 300 housewives was used for each of the thirteen detergent compositions. The women were given the compositions in unprinted cartons identified only by a letter such as "A" or "B," and were asked to use them regularly in dishwashing. The women's hands were examined by physicians before the use of the composition was started and again after about 2 weeks' use of the composition. The examinations were usually made at least an hour after the use of the detergent composition, so that any temporary effect of hand immersion was not visible. The women were asked to use the compositions for all general household use, dishwashing being the most important.

On the basis of physicians' ratings on the effect of the detergent compositions on the hands of the users, the thirteen compositions were arranged in order of mildness. The rank order correlation (see pages 85-87 of "An Outline of Statistical Methods," Arkin & Colton, 4th E., Barnes & Noble)

25

$$\rho = 1 - \frac{6 \sum (D^2)}{N(N^2 - 1)}$$

30 (wherein ρ is the measure of correlation, D is the difference between the two ranks given for each detergent composition, and N is the number of compositions) was computed for the guinea pig tests vs. the doctors' rating; ρ was +.88. In this type of correlation, a perfect correlation is +1.0; a complete reverse order disagreement calculates at -1.0. Thus, a value of +.88 enables us to estimate relative human hand skin mildness from highly exaggerated guinea pig immersion tests.

As used in the following examples, the graded guinea pig immersion tests consist of immersing the animal up to the thorax in the test solutions at 37° C. for a 4½ hour period per day for 3 consecutive days. The animals are graded 3 days after the last immersion. The grades given in the examples are the average of the results on not less than three animals.

It will be understood by those with experience in biological experiments that there is variation in the reactions of individuals, within a group, to exposure to chemical solutions; this is true whether the individuals are guinea pigs or humans.

Example I

The following aqueous solutions were compared in graded guinea pig immersion tests:

	Test Solution	Ratio, Alkylbenzene Sulfonate: Amine Oxide	Grade
60	0.2% sodium dodecylbenzenesulfonate	-----	3
	0.2% lauryl dimethylamine oxide	-----	(*) 5
	0.2% lauryl diethylamine oxide	-----	(*)
	0.2% lauryl dipropylamine oxide	-----	
65	0.133% sodium dodecylbenzene sulfonate plus 0.067% lauryl dimethylamine oxide	2:1	7
	0.133% sodium dodecylbenzene sulfonate plus 0.067% lauryl diethylamine oxide	2:1	7
	0.133% sodium dodecylbenzene sulfonate plus 0.067% lauryl dipropylamine oxide	2:1	7

*Ungraded but extremely irritating.

A significant unexpected mildness effect is apparent in the solutions of mixtures of the above alkylbenzene sulfonate and amine oxide in a 2:1 ratio as compared to solu-

tions in equal concentration, of the individual detergents alone.

Example II

The following aqueous solutions were compared in graded guinea pig immersion tests:

Test Solutions		Ratio, Alkylbenzene Sulfonate: Amine Oxide	Grade
Percent Sodium Dodecyl Benzene Sulfonate	Percent Lauryl Dimethyl Amine Oxide		
0.2	0.01	20:1	3
0.2	0.02	10:1	7
0.18	0.018	10:1	8
0.165	0.033	5:1	10
0.2	0.1	2:1	7
0.133	0.067	2:1	7
0.1	0.1	1:1	10
0.1	0.2	1:2	10
0.067	0.133	1:2	10
0.033	0.165	1:5	5
0.02	0.2	1:10	2
	0.1		5
	0.2		2

Example III

The following aqueous solutions were compared in graded guinea pig immersion tests.

Test Solution	Ratio, Alkylbenzene Sulfonate: Amine Oxide	Grade
0.2% sodium dodecyl benzene sulfonate		3
0.2% sodium alkyl benzene sulfonate (the alkyl group being derived from a mixture of straight chain olefins averaging 12 carbon atoms)		5
0.2% myristyl dimethyl amine oxide		(*)
0.2% cetyl dimethyl amine oxide		2
0.2% oleyl dimethylamine oxide		3
0.2% 2-hydroxylauryl dimethyl amine oxide		5
0.2% 2-diethyl amino ethyl lauramide oxide		3
0.2% sodium dodecylbenzene sulfonate plus 0.1% myristyl dimethyl amine oxide	2:1	9
0.2% sodium dodecylbenzene sulfonate plus 0.1% cetyl dimethyl amine oxide	2:1	10
0.2% sodium dodecylbenzene sulfonate plus 0.02% cetyl dimethyl amine oxide	10:1	6
0.2% sodium alkyl benzene sulfonate (the alkyl group being derived from a mixture of straight chain olefins averaging 12 carbon atoms) plus 0.1% lauryl dimethyl amine oxide	2:1	9
0.2% sodium dodecylbenzene sulfonate plus 0.1% 2-hydroxylauryl dimethyl amine oxide	2:1	9
0.2% sodium dodecylbenzene sulfonate plus 0.1% oleyl dimethylamine oxide	2:1	9
0.2% sodium dodecylbenzene sulfonate plus 0.1% 2-diethyl amino ethyl lauramide oxide	2:1	9

* Ungraded but extremely irritating.

It is apparent from the results set forth in Examples II and III that an unexpected mildness effect of mixtures of alkylbenzene sulfonates and tertiary amine oxides in this invention exists in the ratio range of these compounds of about 20:1 to about 1:5 and that the best mildness effects are seen in the ratio range of about 10:1 to about 1:2.

To illustrate that the amine oxides described in this invention do not appear to exert a significant unexpected mildness effect with other synthetic detergents which reportedly could be made milder, the following aqueous solutions were tested in a graded guinea pig immersion test.

Test solution:	Grade
0.2% sodium salt of sulfated coconut oil fatty alcohol	5
0.2% sodium salt of sulfated coconut oil fatty alcohol + 0.1% lauryl dimethyl amine oxide	5

Example IV

An exaggerated arm washing exposure test was conducted on human subjects using two 10% solutions (A and B) of a granular detergent having the following compositions:

	Percent
Sodium dodecylbenzene sulfonate	17.5
Sodium tripolyphosphate	50.0
Sodium sulfate	16.0
10 Sodium silicate solids having an SiO ₂ :Na ₂ O ratio of 1.6:1	6.0
Monoethanolamide of coconut oil fatty acids	3.0
Moisture	7.5

15 Solution A consisted of the granular detergent composition alone. To Solution B an amount of lauryl dimethyl amine oxide equal to 10% by weight of the detergent composition in solution was added. The solutions were used at 105° F. Ten human subjects participated in the test. 20 The inner aspects (inside) of each elbow of each subject were washed with the solutions, one aspect with Solution A, the other with Solution B. The test consisted of rubbing the aspects for 30 seconds with a 4 inch square terry cloth wash cloth saturated with the test solution. The 25 solution was allowed to remain on the subject's arm for an additional 30 seconds and the arm was then blotted dry. This washing test was conducted on each subject three times daily, morning, midday and afternoon, for three days. The subjects were graded after the final washing on 30 a 1 to 10 scale as described above.

The following results were obtained, with the grade being the average of 10 subjects.

	Grade
Solution A	17.4
Solution B (containing added amine oxide)	9.1

¹ Comparable to soap based laundry detergents.

It has been observed that a solution of a mixture of about equal parts of sodium dodecyl benzene sulfonate and lauryl dimethyl amine oxide effects no thickening and cracking of the skin of animals characteristic of the individual components alone, even in repeated, severe and exaggerated guinea pig exposure tests.

The mild mixtures of alkyl benzene sulfonates and amine oxides in the compositions of this invention are useful as detergents per se or in combination with any of the usual synthetic detergent adjuvants, builders, diluents and additives to produce mild detergent products such as heavy or light duty detergent granules, heavy and light duty liquid detergents, shampoos or detergent bars.

50 The mildness characteristics of the mixtures of alkyl benzene sulfonates and amine oxides of the present invention are useful in any detergent or cleansing composition which comes in contact with the skin in an aqueous medium. Detergent compositions containing the synthetic 55 detergent mixture of this invention can comprise from about 0.5% to 100% of the mixture as an essential detergent and sudsing component depending on the end use. For example, a scouring cleanser can contain as little as about 0.5% of the detergent mixture of this invention or 60 a dry granular detergent composition comprising 100% of the mixture can be used to make a washing solution. In each case the composition containing the mixture of the invention is milder to the skin during use than an equal amount of either of the individual components of the mixture alone. Detergent compositions usually contain about 5% to about 50% synthetic detergent, i.e. the mixture of alkyl benzene sulfonates and amine oxides described in this invention.

65 Amine oxides are advantageously combined with alkyl benzene sulfonates not only for the unexpected mildness which is effected in the combination but for additional qualities which amine oxides impart to alkyl benzene sulfonate compositions.

The mixtures of alkyl benzene sulfonates and amine 70 oxides of this invention are better solubilizers of calcium

soaps and better soil fluidizers than the alkyl benzene sulfonates alone. These detergent mixtures generally have better sudsing characteristics, i.e. suds formation and stability in the presence of soil, than the alkyl benzene sulfonates alone. In general, the heavy duty detergency of the detergent mixtures of this invention is greater than that of the alkyl benzene sulfonates alone.

In the following examples, parts are by weight.

Example V

A mild, heavy-duty, granular detergent composition was made by mixing together the following ingredients:

10 parts sodium dodecyl benzene sulfonate
10 parts lauryl dimethyl amine oxide
15 parts sodium tripolyphosphate
30 parts sodium sulfate

The heavy duty detergency of this composition is excellent.

Example VI

A mild, light-duty, granular detergent composition of excellent efficiency is made by mixing together the following ingredients:

25 parts potassium dodecyl benzene sulfonate
15 parts cetyl diethyl amine oxide
45 parts sodium sulfate
15 parts sodium tripolyphosphate

Example VII

A mild efficient liquid dishwashing detergent which foams well is made by mixing together the following ingredients:

15 parts ammonium dodecyl benzene sulfonate
15 parts lauryl methyl ethylamine oxide
10 parts ethanol
60 parts water

Example VIII

A mild efficient detergent toilet bar is made by dry mixing, milling, extruding and stamping into a bar the following ingredients:

20 parts sodium dodecylbenzene sulfonate
5 parts coconut alkyl dimethyl amine oxide in which the higher alkyl radicals are predominantly the mixture of lauryl and myristyl radicals found in fractionated coconut oil fatty alcohol
10 parts of coconut oil soap
50 parts tallow soap
15 parts moisture

Example IX

A mild shampoo with excellent foaming characteristics is made by mixing together the following ingredients:

10 parts triethanolamine dodecyl benzene sulfonate
10 parts lauryl dimethyl amine oxide
80 parts water

Example X

A mild scouring cleanser which foams and cleans well is made by mixing together the following ingredients:

85 parts silica flour
13 parts trisodium phosphate

1 part sodium dodecylbenzene sulfonate
1 part myristyl diethylamine oxide

What is claimed is:

1. A composition capable of synergistic mildness when used as an active ingredient in a detergent composition, said composition being a mixture of a water soluble alkyl benzene sulfonate having an alkyl radical ranging from about 9 to about 15 carbon atoms and a tertiary amine oxide having the formula $R_1R_2R_3\rightarrow O$ wherein R_1 is an alkyl radical containing from about 10 to about 18 carbon atoms and R_2 and R_3 are each selected from the group consisting of methyl, ethyl and propyl radicals, the ratio of alkyl benzene sulfonate to tertiary amine oxide being in the range of about 10:1 to about 1:2.

2. The composition of claim 1, wherein R_2 and R_3 are methyl radicals and R_1 is a straight saturated chain of from 12 to 16 carbon atoms.

3. The composition of claim 1 wherein R_2 and R_3 are ethyl radicals and R_1 is a straight saturated chain of from 12 to 16 carbon atoms.

4. A mild liquid detergent composition consisting essentially of about 5% to about 50% of the mixture of claim 1 in an aqueous vehicle.

5. A mild granular detergent composition consisting essentially of about 5% to about 50% of the mixture of claim 1, sodium tripolyphosphate and sodium sulfate.

6. The composition of claim 2 wherein R_1 is a lauryl radical.

7. A mild liquid detergent composition consisting essentially of about 5% to about 50% of the mixture of claim 2, water and ethanol.

8. The composition of claim 3 wherein R_1 is a lauryl radical.

9. The composition of claim 6 wherein the alkyl benzene sulfonate is sodium dodecyl benzene sulfonate.

10. A composition capable of synergistic mildness when used as an active ingredient in a detergent composition, said composition being a mixture of about equal parts of sodium dodecylbenzene sulfonate and lauryl dimethyl amine oxide.

11. A detergent composition consisting essentially of a mixture of about equal parts of a water soluble dodecyl benzene sulfonate and dodecyl dimethyl amine oxide, said mixture being capable of synergistic mildness.
